(57) **CLAIM**

The ornamental design for a storage container front panel, as shown and described.

DESCRIPTION

FIG. 1 is a front, right perspective view of my ornamental design for a storage container front panel with the front panel in a closed position, showing my new design;

FIG. 2 is a front elevational view thereof;

FIG. 3 is a rear elevational view thereof taken along the line 3—3 of FIG. 1;

FIG. 4 is a cross-sectional view thereof taken along the line 4—4 of FIG. 1;

FIG. 5 is a front, right perspective view thereof with the front panel in an open position;

FIG. 6 is a front elevational view thereof with the front panel in an open position;

FIG. 7 is a rear elevational view thereof, taken along the line 7—7 of FIG. 5, with the front panel in an open position;

FIG. 8 is a right side elevational view thereof with the front panel in an open position;

FIG. 9 is a left side elevational view thereof with the front panel in an open position;

FIG. 10 is a top plan view thereof with the front panel in an open position;

FIG. 11 is a bottom plan view thereof with the front panel in an open position;

FIG. 12 is a cross-sectional view thereof taken along the line 12—12 of FIG. 5; and,

FIG. 13 is a cross-sectional view thereof, taken along the line 13—13 of FIG. 1, with the front panel in a closed position and illustrating the front panel in an alternative, unclaimed cabinet environment.

The broken lines shown in FIGS. 1-3 and 5-7 adjacent the shaded areas of the storage container front panel represent exemplary bounds of the claimed design and form no part thereof, while all other broken lines showing a cabinet and hardware in FIGS. 1-13 are included for purposes of illustrating an environment of the storage container front panel and form no part of the claimed design.
